UNITED STATES PATENT OFFICE.

WILLIAM W. WALLACE, OF SPRINGFIELD, MASSACHUSETTS.

PIANOFORTE-ACTION.

SPECIFICATION forming part of Letters Patent No. 608,938, dated August 9, 1898.

Application filed September 20, 1897. Serial No. 652,345. (No model.)

To all whom it may concern:

Be it known that I, WILLIAM W. WALLACE, a citizen of the United States of America, residing at Springfield, in the county of 5 Hampden and State of Massachusetts, have invented new and useful Improvements in Pianoforte-Actions, of which the following is a specification.

This invention relates to pianoforte-actions, 10 the object being to provide improved devices for uniting certain parts of said actions, and particularly those which are most subject to derangement caused by changes of temperature and hygrometric variations thereof; and 15 the invention consists in the peculiar construction and arrangement of said part-uniting devices, all as hereinafter fully described and more particularly pointed out in the claims.

20 In the drawings forming part of this specification, Figure 1 is a side elevation illustrating the several operating parts of a pianoforte-action. Figs. 2 to 5, inclusive, illustrate parts and sections of parts of said action having my 25 improvements applied thereto. Figs. 6 and 7 are perspective views of certain parts containing my improvements, which are fully described below.

Referring to the drawings, the parts of the 30 pianoforte-action having operative relations to those parts thereof to which my improvements are directly applied are illustrated, to the end that the practical value of my improvements may be better understood.

35 Referring to Fig. 1, 2 indicates the key-rocker, 3 an upright bearing by its lower end on said rocker, and 4 a support attached to the upper end of said upright 3. The lower flange-rail is indicated by 9 and has secured thereto a jack-rocker flange 5 for each key-action of the instrument, and 10 is a brace between said rocker-flange and said upright 3, having a pivotal connection with said parts 3 and 5. Said support 4 is pivotally connected to the action-rail 7 by a flange 8, which is substantially the same as said jack-rocker flange 5, and said support is pivotally attached to the upper end of said upright 3.

40 A flange 15 of substantially the same construction as the before-mentioned flanges 5 and 8 is secured to the upper edge of said action-rail 7 by a screw *e*, as shown, and ex-

tending horizontally serves as a pivotal support for the damper-lever 14, and another like flange 6 is similarly secured to the inner side 55 of said action-rail 7 and serves as means for pivotal connection of the hammer-shank 12 to said rail, as shown in Fig. 1.

The hammer-spring rail is indicated by 21, the back check by 23, and the hammer-rail 60 by 13.

The above-named parts of the pianoforte-action other than said flanges 5, 6, 8, and 15 are illustrated and referred to in order that the office of said flanges in constituting pivotal supports for parts of the action connected thereto may be made clear.

To persons familiar with the mechanical structure of pianoforte-actions it is well known that the last-mentioned four several 70 flanges, which heretofore have been secured to their holding parts by a common screw passing through a hole formed in the wood thereof and entering the wood of said holding parts, are subject to continuous hard strain 75 when the instrument is being played upon, and, furthermore, that they frequently become loose because of insufficient means of attachment to the fixed parts of the action and because of atmospheric action there- 80 upon, whereby they become loose upon their attaching-screw, and consequently upon said fixed parts, thereby inducing a hard and rattling action, which the within-described improvements entirely obviate. 85

The said improvements in the above-mentioned flange-securing devices are illustrated in certain of the figures above referred to, and they consist in providing an internally and externally screw-threaded socket-lining 90 *c*, having a plain solid inner extremity and having a diameter substantially that of the base of the external screw-thread thereon, which socket-lining is screwed into a socket in the action-rail 7 or other part having normally the diameter of said socket-lining's plain extremity, as shown in Fig. 4, to the end that the latter shall have a bearing in said socket well beyond the screwed part of said lining to brace the latter against lateral 95 movement and to provide for the best possible engagement of the screwed part of said lining with said socket.

Said improvements further consist in pro-

viding a tubular metallic bushing *d*, tightly inserted in and extending from the outer face of the flange through a transverse groove *n* in the rear side thereof and terminating at 5 that point, said groove being adapted to receive a rib on said action-rail and others to which said flange may be attached, and finally a screw *e*, passing through said flange and bushing *d* and screwing into said socket-lining *c*. Said screw has no screw engagement with said bushing *d*. Thus by securing said flanges to their supporting parts, as described, they remain permanently in place, for the outer end of said socket-lining *c* presents a 15 metallic base against which said metallic bushing *d* abuts, and the outer end of the latter and a portion of the surface of the flange immediately surrounding the end of said bushing are compressed under the head 20 of said screw *e*, thus rigidly so holding said flange in place that it resists the normal strain of the action parts thereon and is not subject to derangement from changes of temperature above referred.

25 Further improvements in said pianoforte-action, herein shown in Figs. 1 and 7, consist in providing improved means for uniting the damper-wire 16 and the damper-head 17, whereby a rigid and enduring attachment of 30 said parts is secured, and said attaching parts comprise a screw *a*, having a shank screwing into the damper-block 18 and having an outer screwed extremity receiving a nut *b*, said screw *a* having a cylindrical enlargement 35 midway between its ends, as shown, and a transverse perforation therethrough through which the end of said damper-wire passes, as shown in Figs. 1 and 7. Said transverse perforation is so located in said screw *a* that a 40 half-round groove is formed in one end of said cylindrical enlargement, in which said damper-wire lies, as in Fig. 7, and is thereby when said nut *b* is screwed thereagainst so rigidly held as to resist displacement from 45 the operation of the pianoforte-action.

Having thus described my invention, what I claim, and desire to secure by Letters Patent, is—

50 1. In a pianoforte-action, means for attaching the flanges thereof to a fixed part or parts of said action, comprising an internally-screw-threaded metallic socket-lining secured in

said fixed part, combined with a flange of said action, a metallic bushing passing transversely therethrough, one end of which abuts 55 the outer end of said lining, and a screw passing freely through said bushing having no screw engagement therewith, and by its head engaging the outer end of said bushing, substantially as set forth.

2. In a pianoforte-action, means for attaching the flanges thereof to a part or parts of said action, comprising an internally and externally screw-threaded metallic socket-lining having an inner extremity of the diameter 65 of the base of its external screw-thread, fixed in said socket, combined with a flange of said action having a metallic bushing having no internal screw-thread, passing transversely therethrough, for abutment against the end 70 of said socket-lining, and a screw passing freely through said bushing having its head engaging the outer end of said bushing and the surrounding part of said flange, substantially as set forth.

75 3. In a pianoforte-action, means for uniting the damper-wire and the damper-head thereof, comprising a screw engaging with the block of said head having an outer screwed extremity and an enlargement midway between its extremities, and a transverse perforation therethrough adjoining said enlargement, combined with the damper-wire entering said perforation, and a nut compressing said wire between the same and said enlargement, substantially as set forth.

4. In a pianoforte-action, means for uniting the damper-wire and the damper-head thereof, comprising a screw engaging with the block of said head having an outer screwed 80 extremity and an enlargement midway between its extremities, and a transverse perforation therethrough adjoining the outer end of said enlargement and forming a half-round groove in said outer end, combined 85 with the damper-wire extending through said perforation and engaging said groove, and a nut compressing said wire between the same and said enlargement, and forcing said wire into said groove, substantially as set forth.

100 WILLIAM W. WALLACE.
